TELEVISION APPARATUS

Kalman Tihanyi, Budapest, Hungary, assignor
to Radio Corporation of America, a corporation
of Delaware

Original application June 10, 1929, Serial No.
369,598. Divided and this application March 8,
1935, Serial No. 9,959. In Germany June 11,
1928

5 Claims. (Cl. 178—7.5)

The present invention relates to television apparatus, and is particularly directed to the receiver end of the system. This application forms a divisional part of my copending application Serial No. 369,598, filed June 10, 1929, for an invention entitled Television apparatus.

It is one of the primary objects of the present invention to eliminate many of the difficulties which arise in connection with the methods of 10 reproducing television images as heretofore practiced in the art, with particular reference being had to the difficulties which have arisen in connection with the so-called mechanical types of television apparatus such, for example, as the 15 Nipkow disc. Also in the prior art, so far as I am aware, difficulties have frequently arisen due to the fact that it has been substantially impossible to cause the produced electro-optical effects to persist for any appreciable length of 20 time. Therefore, in accordance with my present invention recourse is had to systems wherein special means are provided for intensifying the 25 picture resulting in the receiving tube of the system assuming the invention to be applied to the so-called cathode ray type of image reproducer. To this end the system is so designed and developed that there is produced in the receiver tube the effect of storage of the image producing 30 signals so that the electro-optical effects which result are maintained substantially throughout the entire scansion cycle.

Other objects and advantages of the invention are to provide improved television reproducing apparatus which will be efficient in its operation, 35 and easy to control.

Still other objects and advantages will be apparent to those skilled in the art by a reading of the following specification and claims taken in connection with the accompanying drawing 40 wherein:

Fig. 1 discloses an arrangement wherein a grid-like structure is combined with an electrode for emitting electrons to control the brilliance of the fluorescent effects resulting.

Fig. 2 shows a modification of the arrangement 45 of Fig. 1;

Fig. 3 illustrates a still further modification; and

Fig. 4 shows, for example, one form of grid 50 structure which might be used in connection with the apparatus disclosed by Fig. 1 although other forms of grid structure could be substituted.

In making reference to the accompanying drawing, image signals transmitted by any desired type of transmitting apparatus such, for example, as that shown in my parent application Serial No. 369,598 above referred to, are suitably received in a receiving device 1 and are supplied to the control electrode system 3 of a cathode ray 55 tube conventionally designated 5. Within this 60

tube, there is developed between a cathode 7 and an anode 9 an electron beam conventionally designated 11 whose intensity is controlled in accordance with the strength of the received signal applied to the control grid 3. At the opposite 5 end of the tube 5, there is provided a fluorescent screen structure 13, and intermediate this screen structure and the point at which the electron beam 11 is developed, there is provided a source of electrons which is provided by means of a series of cathode wires or some other appropriate 10 emitter 15. The electrons emitted from the source 15 tend to flow toward the screen structure 13 by reason of the voltage difference maintained between the emitter 15 and the screen 13 15 by the battery 17 so that in the absence of any cathode ray 11 developed within the tube, there will be substantially constant intensity light produced upon the fluorescent screen structure. Intermediate the emitting surface 15 and the screen 20 13 there is provided a grid-like structure 19 which, for example, may be of the form shown by Fig. 4 so arranged the grid structure 19 comprises an internal conducting member 21 about which is a layer of insulating material 23 extending throughout the entire length of the conductor. Covering the insulator 23 and spaced apart from each other are a plurality of electrically isolated photoelectric areas 25. With the arrangement as described, the electron beam 11 25 developed within the tube passes through the emitter element 15 so as to impinge upon the photoelectric surface 25 and the associated insulator 23 in the area intermediate the independent photoelectric areas. When this happens, it is believed that the positive charge which 30 the photoelectric areas acquire due to the illumination of the screen structure 13 as produced by the electrons from the source 15 impinging upon the same will be neutralized, and thus the intensity of the fluorescent effect resulting will be 35 modified. The charge produced by virtue of the impact of the beam electrons as controlled in intensity by the signal applied to the control grid 3 will vary the intensity of illumination upon the screen structure 13 so that it is proportional to 40 the signal received. This intensity of fluorescent effect will continue during the time interval between successive scansions by the beam.

The scanning action takes place by virtue of 45 any suitable controlling voltages applied to the deflecting systems 27 and 29 which, it may be assumed, are in synchronism with similar controlling voltages at the transmitter end of the system, and thus the developed cathode ray beam 50 is caused to scan each elemental area of the structure 21, 23, 25 at a predetermined rate.

In the modified form of arrangement as disclosed, for example, in Fig. 2, there is arranged 55 intermediate the screen structure 13 and the 60

electron beam developing arrangement comprising the cathode 7 and the anode 9, two additional electrodes which comprise cathode wires such as that shown at 31 and a photoelectric layer such as that shown at 33. The layer or grid 33 with its electric field elements influencing the intensity of the electron current from the cathode wires 31 in a manner substantially similar to that of the ordinary type of two-plate valve in which the cathode is between an anode and an opposite electrode. The grid-like structure 33 and the electrode 31 may also be arranged behind the screen where desired. Any negative charges on the photoelectric grid 33 must be removed or neutralized after the conductor has been transmitted, and this may be done by irradiation with homogeneous light, for example, as indicated conventionally by means of the in-falling light rays designated as 35, and the photoelectric effect which is released thereby will cause the entire grid to be charged to a positive tension, for example, the limit tension, and is then ready for the next operation or, in other words, the next cycle of scansion, and the electrodes released by the homogeneous light beams may be accumulated in any positive portion of the tube, for example, the screen structure itself.

A still further modification of the arrangement, as disclosed by Fig. 3, a cathode is shown at the rear of the fluorescent screen 13. In this showing, 37 represents an insulated plate on the front face of which layers of photo-sensitive material 39, as described above, are provided. Opposite the layers of photo-sensitive material 39 are similar layers 41 which are arranged on the face of the plate 37 which is not struck by the developed cathode ray beam 11. The screen structure 13 with its phosphorescent layer is arranged on the rear face of the system, and electrodes which 40 radiate electric particles, such as the cathode element 43, may be arranged at the rear of the system. The cathode wires are preferably made from a metal having a low cathode drop, and the tube is filled with a rare gas, such as argon, for example, at low pressure. The wires may also be of oxide in red hot condition, and may be coated, for example, with barium oxide. As described in connection with the description of Fig. 3, homogeneous light from a suitable source 35 may be arranged to neutralize the charges at the completion of each cycle of scansion.

While the invention has been illustrated in several of its preferred forms it will, of course, be apparent that many additional modifications 55 may be made without departing from the spirit and scope of the foregoing disclosure.

Having now described one form of the invention and the manner in which it is believed the same may be operated, what is claimed and 60 desired to secure by Letters Patent is the following:

1. In a television apparatus, a cathode ray tube having means at one end thereof to develop an electron beam, an image carrier at the other 65 end of the tube, said image carrier comprising a network of electrically conducting strands having insulating material surrounding each, a plurality of separated light sensitive areas supported upon the insulators, a fluorescent screen and a source 70 of electrons each positioned adjacent said image carrier, and on opposite sides thereof.

2. A cathode ray tube comprising an evacuated envelope containing a screen structure adapted

to fluoresce under electronic bombardment, a source of electrons substantially adjacent the screen structure, a control electrode intermediate the electron source and the screen, means to produce a cathode ray beam and to control the intensity thereof in accordance with received image signals, and means for causing the intensity controlled cathode ray beam to scan the said control electrode to produce at each elemental area thereof during scansion an electrostatic charge to modify the illumination intensity normally produced at the screen structure.

3. In a cathode ray beam comprising an evacuated envelope containing a screen structure adapted to fluoresce under electronic bombardment, a homogeneous source of electrons substantially adjacent the screen structure, a control electrode intermediate the electron source of the screen structure, said control electrode comprising a network of electrically conducting strands having insulating material surrounding each, and a plurality of separated light sensitive elemental areas supported upon the insulators, means to produce a cathode ray beam and to control the intensity thereof in accordance with received image signals, and means for causing the intensity controlled cathode ray beam to scan said control electrode to produce at each said light sensitive elemental area thereof during scansion an electrostatic charge to modify the illumination intensity normally produced on said screen structure.

4. In an electron tube of the cathode ray type including an evacuated envelope, a cathode at one end thereof and an anode to which appropriate voltages are adapted to be applied so as to develop an electron beam, an image carrier in the opposite end of the envelope, said image carrier comprising a network of electrically conducting strands having insulated material surrounding each, a plurality of separated light sensitive elemental areas supported upon the insulators, a fluorescent screen positioned adjacent to and on one side of said image carrier, and a source of electrons positioned on the other side 45 of said image carrier.

5. An electron tube of the cathode ray type including an evacuated envelope, a cathode at one end thereof and an anode to which appropriate voltages are adapted to be applied so as to 50 develop an electron beam, a fluorescent screen structure adapted to fluoresce under electronic bombardment positioned in the opposite end of the evacuated envelope, a source of electrons substantially adjacent said screen structure, a control electrode adapted to control the flow of electrons from said source to said screen structure, said control electrode comprising a plurality of electrically conducting strands having insulating material surrounding each, and a plurality 55 of separated elemental light sensitive areas supported upon the insulators, means for controlling the intensity of the developed electron beam in accordance with received image signals, and means for causing the intensity controlled electron beam to scan the said screen structure and a control electrode to produce at each elemental area of said control electrode during scansion an electrostatic charge to modify the illumination intensity normally produced at said screen 60 structure.

KALMAN TIHANYI.
